UNITED STATES PATENT OFFICE.

JOSEPH M. SCALLEN, OF SAN FRANCISCO, CALIFORNIA.

GARMENT SUPPORTER.

Application filed March 4, 1924. Serial No. 696,834.

This invention relates to fasteners as used on articles of clothing in place of buttons, and has for its particular object a device of this character particularly adapted for use 5 on men's trousers to engage with ends of the suspenders and with the upper edge of the drawers.

I carry out my invention by the structure shown in the accompanying drawing, and 10 while the drawing shows a ready means of carrying it out, any other arrangement may be used which will come within the scope of the invention.

The garment supporter shown in the drawing 15 may be made from wire. Assuming that it is made from wire, a loop 4 is formed at one end of the wire. This loop is a sewing loop, that is, it affords means whereby the device may be securely fastened to a garment. After forming a loop, the wire is bent to form a U-shaped section 5. At the 20 top of the U-shaped section 5, the wire is brought forwardly, downwardly and then upwardly forming a hook 6 which is made double by bending back the succeeding portion of the wire along the path taken by the loop 6, thus forming a double loop which is substantially at right angles to the loop 5.

After forming the mentioned double loop, the wire is bent to form a second U 7, the 30 legs of which are in the same plane as the legs of the U 5. The two U's thus form a W. Another sewing loop 8 is formed at the outer end of the U 7.

In employing the invention, the device 35 shown in the drawing may be sewed to the trousers at the eyelets or loops 4 and 8 and also along the legs of the W if desired. The suspenders may be positioned between the loop 6 and the legs of the device which form 40 the letter W, while a strap fastened to an undergarment is hung on the loop 6.

I claim:

A garment supporter of the character described comprising a wire bent to the form 45 of a W with all arms on a common plane, the upper free ends of the W being each formed into a sewing loop, and the central legs being elongated and bent forwardly and down, then again forwardly and up so as to 50 form two open hooks one directly back of the other, the forward hook being adapted to suspend an article and the rearward hook adapted to suspend the hook on an article.

JOSEPH M. SCALLEN.
